21 Claims. (Cl. 179—9)

1

The present invention is concerned with call recording arrangements for use in telephone systems and while in particular it is applicable to arrangements of the type whereby calls can be recorded automatically against calling parties on punched cards or tickets it has application to manual recording arrangements if the full automatic equipment is not desired.

It is an object of the invention to provide a comparatively inexpensive and efficient call recording system of the above type and preferably one in which use is made of accounting machines of known mechanical or electromechanical types such as are often already employed by telephone administrations.

The number of local fee calls or calls which are registered on subscribers' meters per day on a large telephone exchange is very high and may be of the order of 100,000 for a busy 10,000 line exchange. To produce individual tickets or cards for each of these calls is obviously out of the question due to the large amount of tickets involved. The object of the invention is to provide an automatic record while keeping the number of tickets within reasonable bounds.

According to one feature of the invention a connection is set up periodically between subscribers' line equipment and recording equipment to enable the aggregate value of calls chargeable against a subscriber to be ascertained. According to a second feature of the invention a circuit change is brought about in a subscriber's line equipment each time a predetermined aggregate value of calls is registered against said subscriber, provision being made to prevent the circuit change persisting after a record has been made. The predetermined aggregate value of calls may conveniently vary with the calling rate of the individual subscriber.

For a lightly used residential telephone a ticket might be issued for a block equivalent to ten unit fee calls, while for heavier loaded installations blocks of twenty, fifty and one hundred unit fee calls per ticket are proposed. Hence the number of tickets for the above-mentioned type of exchange may be reduced to the order of 2,000 per day, and if they are made reasonably small in size the handling of such quantities should present no problem.

According to one feature of the invention each time a predetermined aggregate value of calls is registered against a subscriber the identity of the subscriber is automatically ascertained and recorded, for instance, the identity may be trans-

2

ferred to a common position where a record may be made either manually or automatically.

According to a further feature of the invention, recording equipment is operated independently of a connection between two subscribers to record block unit calls against subscribers over whose lines the aggregate value of calls made reaches a predetermined value.

According to a further feature of the invention 10 an arrangement is provided according to which each time a certain value of calls has been registered against a subscriber a signal is operated to cause automatic recording apparatus to be set in operation to record the designation 15 of the subscriber. Preferably a counting arrangement is associated with each of a number of subscribers' lines and is adapted to be operated step-by-step in accordance with the value of calls, storage means being provided for causing 20 a signal to be given each time a counting arrangement is operated through a predetermined extent to enable the charge to the subscriber to be recorded in multiples of the units registered on the counting arrangement. For this purpose 25 a momentary contact may be made each time the counting arrangement or meter is operated past a certain position or positions to cause the storage device to operate, the operation of said storage device in turn controlling the operation of common equipment to cause the number of the 30 line with which the storage device is associated to be recorded and the storage device to be restored in readiness to be again operated when the meter again reaches the said position or if there are more than one of said positions, the 35 next position. Conveniently the ticket is punched or printed with the value of the calls against the number of the subscriber.

The storing of the block values of calls may be 40 conveniently effected by a relay with a locking circuit but as this would mean a relay for each line a further feature of the invention concerns the employment of a gas discharge device to perform the functions of a relay whereby a considerable saving may be effected as regards the 45 cost of equipment individual to a subscriber's line. This feature while particularly applicable to the storage of a block value of calls has also more general application such as the replacement of a line relay and consists essentially of a momentary contact being adapted to cause the striking of a gas discharge tube, the circuit being maintained at a lower voltage independent of the momentary contact and the discharge tube being restored to normal by having its terminal short circuited.

Alternatively to gas discharge means a condenser might be employed but this would involve a different arrangement for starting the recording, for instance the finders might be operating continuously. A further alternative might be the shunting of the neon tube by a condenser so that the condensers would retain a detectable charge after the discharge had been extinguished.

These and other features of the invention will be better understood from the following description of one method of carrying the invention into effect, reference being had to the accompanying drawings comprising Figs. 1-3 which should be arranged side by side, with Fig. 1 on the left, to form a circuit diagram of a completely automatic equipment for aggregating and ticketing local fee calls. Such calls have been hitherto usually recorded on a meter mechanism individual to each subscriber, the meters being usually mounted together on a separate rack so as to facilitate the reading or photographing of their indications for accounting purposes. For unit fee calls the meters are operated once where calls of higher value are registered in the meter, the meters are operated twice or more times according to the value of the call, while where the calls are charged for on a duration basis the meter may be repeatedly operated for a single call.

For the purpose of aggregating the total charge to be made to each subscriber, use is made of a counting device similar to subscriber's electro-mechanical step-by-step meter mechanism but modified to provide a fleeting electrical contact each time a predetermined number of calls is registered.

As is known to those versed in the telephone art, the subscriber's meter consists of an electro-magnet, the armature of which operates a set of counters via a ratchet and pawl mechanism; the counters of a four digit meter comprising units, tens, hundreds and thousands wheels. The thousands and hundreds wheels are not required in the present instance and can be removed while the tens wheel can be replaced by a commutator kind of wheel having an insulated surface on its periphery provided with a number of metal inserts which number will vary according as to whether a subscriber requires a ticket for every ten calls such as a residential telephone subscriber, a ticket every twenty calls, a ticket every fifty calls or a ticket every hundred calls. The metal inserts will be connected electrically to the shaft and frame of the meter while an insulated contact spring will be supported from the frame to make electrical connection with a metal insert while the commutator wheel is moving from one position to the next while being out of electrical connection, while the commutator wheel is stationary. In this way a momentary earth connection will be made to the insulated contact spring every time it makes contact with a metal insert which will take place ten times, five times, twice or once during a revolution of the commutator wheel according to the subscriber concerned. Obviously a new mechanism could be designed of much more compact construction. Separate commutator wheels for each kind of subscriber could conveniently be constructed or alternatively insulation pieces instead of metal inserts could be provided in positions where metal inserts are not required.

Referring now to Fig. 1, this shows on the top left-hand side a meter mechanism MTR of a subscriber on a typical automatic exchange, which mechanism is assumed to be mounted in standard

manner on a meter rack and to be wired out to the multiple or the numerical side of the intermediate distribution frame I.D.F. over which connection can be had with the associated subscriber's line circuit in known manner. The inset Fig. 1A shows a possible alternative for new exchanges which in a manner to be later described enables the amount of exchange cable required to be reduced.

The mechanism MTR is provided with a make contact *mt* which closes momentarily after a predetermined value of calls has been registered, which in the case of unit fee calls would be the same as the number of effective calls (i. e. calls which have to be charged for), and in so doing effects storage of the unit on a storage device individual to each subscriber. In this instance the storage device takes the form of a neon tube which is normally primed to a value which is insufficient to cause it to strike, but which will enable it to maintain a discharge once it has been struck as a result of the closure of the contact *mt*. Other methods of storing the bulk unit such as condenser storage arrangements and the like could be employed but the above arrangement appears to offer the most practicable solution. Neon tubes need only be of a very small cheap construction with a wired-in mounting and so occupy little mounting space. The associated resistance required per subscriber can also be of the small inexpensive type as used in radio work.

The neon tube when caused to strike in response to the registration of a bulk unit stores the unit by the discharge being maintained and at the same time starts up the identification finder switches SF (Fig. 1) and PF (Fig. 2). The setting of these switches provides an indication of the number and the class of the subscriber whose neon tube has been located, and this indication is obtained from the switches by a further switch PC (Fig. 3) which transfers it to the solenoids of a punching mechanism, whereupon a ticket characteristic of the subscriber's number and his class is punched, and provides the record of a bulk unit comprising 10, 20, 50 or 100 local fee calls. It will be understood that while a punched ticket enables the cards of various subscribers to be automatically segregated by known mechanisms, the invention is not limited thereto as printed tickets could be sorted manually.

The finder switch SF shown in Fig. 1 comprises a 25 point reverse drive electromagnetically operated step-by-step uni-directional switch of known type with its wipers arranged in pairs, one of the pair being at 180 degrees relationship with the other of the pair, so as to give a capacity of 50 points. Two pairs of wipers and banks SF¹ and SF²; SF³ and SF⁴, are moreover provided so as to give a capacity of 100 points, discrimination as to the particular bank utilised being effected by relays KA and KB in Fig. 2. One such switch is provided per 100 group of subscribers, and the position it takes up determines the tens and units digits of the particular subscriber in question.

The remainder of the equipment required for recording purposes would depend on the size of the exchange and could conveniently for a 10,000 line exchange consist of a two motion 100 point selector switch operating as a finder switch which, in conjunction with the subscribers' finder uni-selectors mentioned above, would cater for 10,000 lines. For flexibility purposes, however, so that the scheme can be readily applied

to the smaller type of exchanges which are more normally encountered, use is preferably made of a uni-selector type of common access switch which, with twenty-five sets of outlets would cater for 2,500 lines, while four such units would together cater for a 10,000 line exchange.

A 2,500 line unit of this type is shown in part of Figure 1, Figure 2 and in Figure 3 and includes a uniselector switch PF together with marking-potential testing equipment comprising thermionic valves and associated relays. Also provided in this unit is a so-called subscriber's marking switch S which sets itself to a position in accordance with the position of the subscriber's finder switch SF and so enables the indication provided by the position of the latter switch to be transferred into the common equipment in readiness for registration. The unit also includes the control uniselector PC which is common to the exchange and which serves to transfer in turns the indications from the switches PF and S to the common punching equipment, the solenoids of which are shown at the left of Fig. 1.

Considering now the operation of the circuit, when a bulk unit has been registered on meter MTR the contacts *mtr* are closed momentarily, and in so doing extend the 50 volts exchange battery via the comparatively low resistance YA (common to 100 subscribers), common lead 13, meter contact *mtr*, neon tube NT, and common lead 11, winding of relay CR in parallel with rectifier MRA in a conductive direction, to an auxiliary 50 volts positive battery which may be that employed for booster battery metering purposes. The two batteries assist one another in this condition and as a result 100 volts is applied across the neon tube NT, whereupon it flashes and relay CR operates. As will be described later the resistance of rectifier MRA in a conductive direction is not sufficiently low to prevent relay CR operating.

When the metering contact *mtr* opens, the discharge of neon tube NT is maintained by virtue of the permanent circuit which is provided therefor over resistance YB and common lead 12 to which is connected a tapping of the order of 20 volts off the 50 volts exchange battery. The 20 volts tapping together with the 50 volts positive battery give a potential of 70 volts, but owing to voltage drop in resistance YB due to the current flow resulting from the striking of the tube, the tube itself will receive a potential less than this value. This potential is, however, sufficient to maintain the discharge of the tube, but it will be understood that 70 volts potential acting alone is insufficient to bring about the initial discharge of the neon tube so that a permanent circuit of the type described can be connected up to the tube without causing any possibility of false operation.

Relay CR in the subscriber's finder equipment is common to one hundred subscribers' meters, and it is therefore possible that more than one neon tube in a hundred group will be in a flashed condition at any one time. To ensure that the potential drop across relay CR (and therefore across neon tube NT when in the discharged condition after contact *mtr* has restored) remains substantially constant irrespective of the number of neon tubes taking current therefrom, use is made of the non-linear voltage/current characteristic of the metal rectifier MRA bridged across it. With one tube only in the discharged condition, the current flow through relay CR will

be very small and the potential drop across it correspondingly small. The voltage/current characteristic of the dry contact rectifier is such that with a small applied voltage its resistance is high, even though it is in a conductive direction, and hence it will impose little shunting effect on relay CR. With two neon tubes in the flashed condition the voltage drop across relay CR will tend to be greater, and hence the metal rectifier will lower its resistance and will so maintain the total voltage drop across this part of the circuit at substantially the original value.

Relay CR in operating at its armature *cr1* extends earth on to common lead 14 extending to 15 the number register equipment associated with the 2,500 lines unit of which the calling subscriber's line forms part, and at its armature *cr2* extends a marking battery via resistance YC on to a contact in the bank of wiper PF4 corresponding to the particular hundred group in the above 2,500 line unit. The earth extended over common lead 14 completes a self-interrupted driving circuit for magnet PFM via contacts *ka1*, *cf1* and interrupter contacts *pfm*. The switch PF thereupon rotates its wipers until wiper PF4 encounters the marking battery applied by armature *cr2*. When this occurs the low resistance relay CF (Fig. 2) operates in series with resistance YC and at armature *cf1* opens the magnet driving circuit and completes an operating circuit to relay TS.

Relay TS in operating at its armatures *ts1* and *ts2* connects up the grids of the testing thermionic valves VA and VB to the wipers PF1 and PF2, at armature *ts3* completes heating circuits for the filaments of the valves via the resistances YD and YE and at armature *ts4* extends earth over armatures *sb1*, *sa1* and *ka4*, wiper and bank PF3, interrupter contacts *sfm* and magnet SFM of the 35 finder switch SF serving the hundred line group in which the meter MTR is located. Magnet SFM thereupon operates in a self-interrupted circuit to rotate its wipers in search of a position corresponding to the calling meter.

Testing for the particular meter calling is effected in the following manner. When a neon tube is in the extinguished condition, the potential at the point under test is, owing to the practically infinite resistance of the unstruck neon tube, that of the battery tapping connection connected to common lead 10, in this case 20 volts negative with respect to earth. Resistances YD and YE in the filaments of the valve circuits VA and VB are of such value that the filaments will be at a potential of the order of 16 volts negative to earth, and hence if either of the wipers PF1 and PF2 encounter an undischarged neon tube, then a potential 20 volts negative with respect to earth will be applied to the grid of the associated thermionic valve, thereby rendering the particular grid in question negative with respect to the filament, so that no anode current will flow to operate the anode relay SA or SB. Rotation of the SF switch wipers will therefore continue until one or other of the wipers encounters the neon tube which is in a state of discharge (i. e. with a stored bulk unit thereon), whereupon a potential much less negative to earth than 20 volts negative will be encountered. In the present case, the tube NT in discharging and consequently lowering its resistance causes the potential of the point under test to move away from 20 volts negative to earth and to advance towards 50 volts positive to earth owing to the voltage drop in the resistance YB. Assuming a current of two mil-

amps is flowing in the neon tube locking circuit and that resistance YB is 10,000 ohms resistance, then 20 volts will be dropped across resistance YB and the point under test will therefore be at earth potential. Provided this point is reduced to a value less than 16 volts negative with respect to earth, which is the mean valve filament potential, then the thermionic valve grid in question will be rendered positive with respect to its filament and will allow anode current to flow such as will operate the magnet drive tripping relay SA or SB as the case may be.

In case any one of the wipers $SF1$ — $SF4$ of the switch SF should encounter a contact connecting with a closed meter contact, a potential heavily negative with respect to earth will be obtained owing to the comparatively low resistance of resistance YA , and hence the thermionic valve will not come into operation. A permanently sticking meter contact will not therefore interfere with the registration of the readings of other meters in the exchange.

It will be noted that the grids of the valves VA and VB are permanently connected to a 20 volt tapping on the exchange battery via the resistances YG and YH and it will be understood that these resistances which are of very high value, of the order of 2 megohms, merely serve to maintain at all times the potentials on the valve grids negative with respect to the filaments, so as to prevent premature operation of the relays SA and SB or possible holding up of these relays after they have been operated; owing to the high value of the resistance this permanent connection to the valve grids does not interfere with the testing functions of the valves.

Returning again to the description, it will be assumed that relay SA operates thereby indicating that the meter MTR in question is in the first fifty of a 100 line group. Relay KA is therefore operated and at its armature $ka1$ disconnects the operating circuit for the slow-to-release relay TS . During the release of this relay, 50 volts positive potential is extended via resistance YF , armatures $kb1$, $ka2$ and $ts1$, wipers and banks $PF1$ and either $SF1$ or $SF2$ and lead 12 so as to short circuit and extinguish the glowing neon tube, and to release relay CR . The same armature $ka2$ also causes the anode current flow in the thermionic valve VA to cease, whereupon relay SA restores. No circuit can however be recompleted to the switch magnet SFM since the circuit thereto is disconnected at armature $ka4$. A locking circuit is completed for relay KA independently of the armature $sa1$ at armature $ka1$. At armature $ka5$ an earth potential is extended over wiper and bank $PF4$ on to the wipers $SF5$ and $SF6$ of the subscriber's finder switch, and at armature $ka5$ (Fig. 3) an earth potential is extended over resting armature $ns1$ to complete a self-interrupted driving circuit for the magnet SM of the marking switch S via its interrupter contacts sm . The switch S thereupon rotates its wipers until wiper $S7$ or $S8$ encounters the earth marking extended on to bank $SF5$ or $SF6$ from armature $ka8$, whereupon an operating circuit will be completed for relay NS which in operating cuts the driving circuit of magnet SM at armature $ns1$ (Fig. 3), and at the same armature extends a start earth over common lead 15 into the exchange puncher control unit in order to signal that full particulars of a block metering unit are available for recording.

If the subscriber in question had been in the second fifty of a 100 line group, then valve VB would have come into operation to bring up its

anode relay SB . Relay SB functions in similar manner to relay SA . The operation of relay SB completes a circuit for relay KB at $sb1$ which in turn at $kb2$ completes a circuit for relay KA . The operation as far as relay KA is concerned is as before, relay KB modifying certain circuits as described hereinafter. In this way if relays SA and SB should both be operated simultaneously as might be the case the recording of the bulk unit represented by relay SB will have preference. At armature $kb1$ (Fig. 2) the neon tube extinguishing potential is extended from resistance YF over armature $ka3$ and $ts2$, wiper and bank $PF2$, wiper and bank $SF3$ or $SF4$ and thence to the neon tube in question. Armature $kb2$ (Fig. 2) in addition to providing an operating circuit for relay KA also provides a locking circuit for relay KB . Armature $kb3$ (Fig. 2) extends a circuit to wiper $PF8$ instead of wiper $PF7$ while at armature $kb4$ (Fig. 3) the marking switch wipers and banks $S3$ and $S4$ are brought into operation instead of wipers and banks $S1$ and $S2$ for a reason which will be appreciated in the ensuing description.

The operation of relay NS indicates that the marking switch S has been positioned on a contact corresponding to the position occupied by the subscriber's finder switch SF , and at the same time indicates that all particulars of the block metering unit in question are available. The puncher control uniselector PC is now set into operation first of all to find the particular 2,500 line group involved.

In the case of a 10,000 line exchange there are four such groups, and the particular group involved is marked on bank $PC1$ or $PC2$ by armature $ns2$ of relay NS in the number register equipment serving it so that when magnet PCM of switch PC is operated in a self-interrupted driving circuit including armature $cs2$, magnet interrupter contacts pcm , common lead 15 and armatures $ns1$ and $ka5$ to earth, its wipers are rotated until earth marking potential is encountered by wiper $PC1$ or $PC2$.

For the purpose of example it will be assumed that the 10,000 line exchange in which meter MTR is located is situated in an area employing a five digit numbering scheme, and that all subscribers have 5 digit numbers commencing with the digit "4." It will be further assumed that the number of the meter is 42311 so that it will be in the first 2,500 line group in the exchange.

Each 2,500 line group involves use of eight consecutive contacts in the switch banks $PC1$ and $PC2$ and in the present instance the first eight contacts will be required for determining the settings of the switches PF and SM . Accordingly the relay NS shown in operating will mark contact 1 of bank $PC1$ with an earth potential over contact $ns2$. Relay CS will therefore operate immediately and at its armature $cs2$ will disconnect the driving circuit to the magnet PCM before this magnet has time to move its armature away from the normal position, and the wipers of this switch will therefore remain in position 1. Relay CS in operating at its armature $cs1$ prepares a locking circuit for itself over multiplied contacts of switch PC and at armature $cs2$ completes an energising circuit for the slow-to-operate-and-release relay IS by way of the magnet interrupter contacts pcm . Relay IS in operating at its armature $is1$ energises the slow-to-operate-and-release relay IP , and this relay in turn at its armature $ip1$ extends earth on to the wipers $PC3$ and $PC4$, the banks of which are wired out to the four groups of 2,500 lines in the exchange, the wiring to the 2,500 line group

in question only, however, being shown, while at armature *ip2* it completes an energising circuit for magnet PCM. Magnet PCM in energising opens its interrupter contacts *pcm* and thereupon opens the circuit for relay IS. This relay releases after a short interval and disconnects relay IP, whereupon after a further short interval PCM magnet circuit is opened and the magnet in releasing then advances the switch wipers to position 2. Relays IS, IP, and the magnet PCM continue to interact and cause the PC switch wipers to be advanced step-by-step round the banks at a speed governed by the release times of the relays.

The ten thousands' digit 4 of the subscriber's number is common to all subscribers in the exchange, and hence the second contact in the selected group in the bank PC3 can be directly wired via a simple cross-connection frame TTF, to the punching mechanism solenoid 4 (Fig. 1). When wiper PC3 encounters contact 2 earth is thereupon extended over wiper and bank PC3, the cross connection frame and the connecting cable to energize the puncher solenoid 4 so as to cause this number or a mark indicative thereof to be punched on a card or ticket.

In case the required number should comprise only four digits, this contact on the switch bank PC3 would be wired out to the puncher spacing solenoid SS so that the card or ticket will be displaced a distance corresponding to one character in readiness for the reception of the thousands digit from the puncher control equipment.

Contacts 3 and 4 on bank PC3 are wired out to wipers PF5 and PF6, the position of which determines the thousands and hundreds digits respectively of the meter MTR. In the present case, since these digits are respectively 2 and 3, they will be indicated in the following manner. The switch PF serves to determine the particular hundreds group in which the discharged neon tube is located, and since in the first 2,500 line group in the exchange the thousands digit of the subscriber's numbers can be any of the digits 1, 2 or 3, the twenty-five contacts in the banks of switch PF can be divided up into two groups of ten and one group of five. If the wipers of this switch occupy any one of the first ten contacts in the bank then the thousands digit will be 1, while if they occupy any of the second ten contacts in the bank the thousands digit will be 2. Similarly, the hundreds digit can be determined in accordance with the particular contact in the bank on which the PF wipers are situated. In the present case these wipers will be positioned on a contact 13 so that the thousands digit determining wiper PF5 will signal a thousands digit 2 to the puncher mechanism solenoids and the hundreds digit determining wiper PF6 will signal a hundreds digit 3. As regards the bracketed numerals associated with these banks PF5 and PF6, an explanation will be given later.

In a similar manner the tens and units digits can be obtained from the banks of the subscriber's marking uniselector S. For signalling tens and units digits 1 and 1 respectively switch S will have its wipers positioned as shown on contact 1 and relay KB will be unoperated so that the puncher control switch wiper PC3 on reaching contact 5 will extend an earth over resting armature *kb4* and wiper S1 in position 1 to energise the solenoid 1 for the tens digit, while when wiper PC3 reaches position 6 it will extend an earth over wiper S5 in position 1 to energise the solenoid 1 again for the units digit. In case the subscriber had been in the second fifty of the

hundred line group, then relay KB would have been operated, and, with the S switch wipers in position 1 the subscriber's tens and units digits would have been 61.

The complete number 42311 has now been punched on a card or ticket and it is now necessary to record thereon the class of the particular subscriber involved in order that the value of the ticket can be assessed. When the puncher control switch wipers reach contact 7 it will be seen that earth is extended in the present instance over resting armature *kb3*, wiper and bank PF7, and wiper and bank SF7 or SF8. Contacts of these banks are wired out over a simple cross connection frame CCF to the punching solenoids 1, 2, 5 or 0 so that a mark or number characteristic of the class of the subscriber involved can be recorded on the ticket.

When the switch PC reaches the eighth and last contact in the selected group relay RR therein is operated and at its armature *rr1* (Fig. 2) releases relay KA (and relay KB in addition if this has been operated) whereupon relay NS is released and the circuit to relay IS in the puncher control equipment is opened while at the same time relay CS therein is also restored to normal so that the equipment is now in readiness for further use.

It will be noted that none of the switches are of the homing type so that hunting for a new position, in response to the completion of a bulk unit on another meter, will take place from the position which they occupy at the conclusion of the previous set-up. The recording of local fee calls in bulk units against other subscribers on the exchange will be appreciated on examination of the wiring arrangements to the banks of the switches PF and SM in Figs. 2 and 3. In this connection it should be understood that the figures shown in brackets against the thousands and hundreds digit determining banks PF5 and PF6 (Fig. 3) refer to the connections of equivalent banks to the punching magnets in number registers associated with other 2,500 line groups on the exchange. Thus while number 3488 will be in the first 2,500 line group and will be marked on the 24th contacts of PF5 and PF6 jointly, the number 3688 will be marked on the 21st contact of contacts of another pair of wipers similar to PF5 and PF6 and connected to the appropriate contacts of switch PC3 attached to the second 2,500 line group.

From the foregoing description it will be seen that the arrangements according to the invention, whereby local fee calls are adapted to be aggregated into bulk units which are stored prior to collection, possess the advantage that a subscriber can continue with the accumulation of a second bulk unit before the first stored unit has been registered by the exchange punching mechanism, it being only necessary to ensure that before the second block has been completed the effect of the storage of the first block has been removed.

There is no difficulty therefore in ensuring that however fast calls are set up by a subscriber, all his effective calls will be recorded even if other subscribers should be completing their blocks of calls at the same time and requiring the service of the identification equipment and of the punching mechanism.

In the case where there is more than one unit awaiting collection and registration then if all the meters concerned are in the same 2,500 line group the switches SF and PF in the associated number register equipment will position them-

selves on the first meter marking to be encountered. The bulk unit stored thereon will then be collected and registered after which, since one or more relays CR will still be operated, the switches will hunt again for a new position and the bulk unit stored in a second neon tube will be registered, and so on. If the meters concerned are in different 2,500 line groups then the order in which the bulk units are collected will be dependent on the order in which the associated groups appear on the banks of the puncher control switch PC.

Although in the arrangement described a puncher mechanism is assumed to be provided per exchange, since its holding time is very small, of the order of two seconds, it may prove worthwhile to arrange for one such mechanism to serve a number of exchanges in an area. Arrangements would of course have to be made to ensure that the puncher mechanism could be associated with one exchange only at any one time, and this could be effected by connecting the puncher to the wipers of a finder switch, the banks of which would connect with a number of exchanges. When any number registering mechanism wished to extend particulars to the common punching mechanism the finder switch would be caused to associate itself with the particular exchange in question and particulars could then be extended forward, possibly in code so as to reduce the number of conductors between the various exchanges and the common point, after which the puncher would be freed to deal with details from other exchange registering equipments.

In the above connection the puncher mechanism might be located for instance in the main exchange of an area and tickets could be transferred daily to the accounts branch; alternatively, the puncher mechanism could be located in the accounts branch, in which case the exchange staff would not be concerned in any way with registration.

The tickets delivered from the punching mechanism will be preferably fed into an automatic sorter and then arranged in trays containing a compartment per subscriber. When it is desired to make up a subscriber's account the relevant tickets could then be counted, multiplied by the appropriate bulk unit charge, and recorded on the account either manually or by automatic accounting machines.

Since incomplete bulk units are not registered they will be automatically transferred to the next account.

Considering now the mounting of the equipment and the exchange cabling required therefor, the general case of exchanges of the step-by-step type will be considered. In the case of existing exchanges the meter mechanisms will be mounted in the usual manner on meter racks and will connect with the various subscribers' line circuits over cables which extend thereto via the intermediate distribution frame I. D. F. The neon tube and associated resistance provided per subscriber may be mounted on the meter racks in which case the meter contacts may be wired directly thereto or alternatively the neon tube and associated resistance might be mounted on the final selector racks in which case a single lead from each meter contact will extend via a cable to the associated neon tube. The subscriber's finder switch SF and associated relay and resistance will preferably be mounted on the final selector rack and the remainder of the equipment which operates on a more common basis will be

conveniently mounted on the alarm equipment rack. In the case of new exchanges use can be made of the invention to avoid the use of separate meter racks by arranging to mount the separate meter mechanisms on the associated line finder or line switch racks so that the exchange cabling hitherto required will be avoided. In this case as is briefly shown in the inset Fig. 1A, the neon tube and associated resistance per subscriber will be mounted on the final selector rack and a single lead from each meter contact will be extended via a cable and the I. D. F. to the associated neon tube. By this arrangement therefore in which the meter mechanisms are mounted on the local side of the I. D. F. as distinct from the multiple side as in the general case hitherto, a saving in exchange cable is effected since only one cable wire per meter is required.

The method of identification described is not essential as any known method of identification may be employed, for instance, the method according to which potentials are placed on different lines at different instants in a cycle as described in the applications of R. Taylor and G. T. Baker, Serial Nos. 321,783 and 380,226 filed March 1, 1940 and February 24, 1941.

It will be appreciated that it is desired to cover the invention in its broadest aspects and that arrangements other than those specifically described and illustrated are intended to fall within the scope of the appended claims.

It will be understood that the principal feature of the invention is directed to recording the charge against a subscriber in bulk instead of individually and preferably in block units each equivalent to a charge of a predetermined number of unit fee calls instead of to registration on a subscriber's individual meter or to the recording of each individual call.

It is not essential to the invention that the recording should be done in such a way that the tickets can be automatically sorted as of course the sorting could be done manually; similarly it is not essential that the recording should be done automatically as an attendant could be signalled and the necessary information notified to her for instance by a call indicator to enable her to make out the ticket manually.

It will also be understood that the method of registering the block unit need not necessarily consist of a counting arrangement as in the usual subscriber's meter but may equally well consist of any form of integrating arrangement such as an electric watt-hour or ampere hour meter.

What we claim as new and desire to secure by Letters Patent is:

1. In a telephone or like system having subscribers' lines and equipment for extending calls from said lines, apparatus common to said subscribers' lines, means for associating said apparatus with any one of said lines after a plurality of calls have been extended from that line, and means in said apparatus operated responsive to said association of the apparatus with said line for registering all of said calls.

2. In a telephone or like system having a subscriber's line and means for making calls therover, means for automatically connecting with said line at intervals and, upon each such connection, registering all calls made over the line during the preceding interval.

3. In a telephone or like system having a subscriber's line and means for making calls from said line, a register normally dissociated from said line, means for associating said register with said

line periodically and, upon each such association, operating said register in accordance with the fee chargeable for all calls made from said line since the last such association of said register with said line.

4. In a telephone or like system having a subscriber's line extending to an exchange and equipment for making calls from said line, means at said exchange governed by one such call from said line for registering that call and at least one call made previously from said line.

5. In a telephone or like system, a plurality of subscribers' lines, means for registering individually each call made from each of said lines, and means common to said lines controlled by said last means for registering, in blocks, the calls made from each of said lines, each said block including more than one call.

6. In a telephone or like system, a subscriber's line, means controlled over said line for registering calls made from said line on a unit call basis, and means controlled by said last means for recording calls made from said line on a block call basis.

7. In a telephone or like system wherein a certain value is assessed to each telephone call, a plurality of subscribers' lines, a recorder, means for identifying any one of said lines responsive to that line making a group of successive telephone calls aggregating a predetermined value, and means controlled by said last means for operating said recorder variably in accordance with the identity of said one line.

8. In a telephone or like system having a plurality of subscribers' lines and means for including each of said lines in different telephone connections at different times, each such connection having an arbitrary value assigned to it, means controlled by each telephone connection for registering, against the subscriber's line included in said connection, the value of that connection, and means controlled by said registering means for identifying the line of any one of said subscribers responsive to the aggregate value of connections registered against that line reaching a predetermined total.

9. In a telephone or like system having a plurality of subscribers' lines and means for including each of said lines in different telephone connections at different times, each such connection having an arbitrary value assigned to it, a register individual to each said line operated to register the value of the different connections in which that line is included, apparatus common to said lines, means controlled by the register individual to any one of said lines for seizing said apparatus responsive to the aggregate value of connections registered by that register reaching a predetermined total, and means controlled by said apparatus responsive to said seizure for recording the identity of said one line and the aggregate value of connections registered by the register individual to said one line.

10. In a telephone or like system having a plurality of subscribers' lines and means for including each of said lines in different telephone connections at different times, each such connection having an arbitrary value assigned to it, a register individual to each said line operated to register the value of the different connections in which that line is included, apparatus common to said lines, means controlled by the register individual to any one of said lines for seizing said apparatus responsive to the aggregate value of connections registered by that register reaching a predetermined total, and means controlled by said apparatus responsive to said seizure for recording the identity of said one line and the aggregate value of connections registered by the register individual to said one line.

a predetermined total, and a common register in said apparatus operated, responsive to said seizure, in accordance with the registration of said register individual to said one line.

5. 11. In a telephone or like system having a subscriber's line and means for including said line in different telephone connections at different times, each such connection having an arbitrary value assigned to it, means controlled by each connection for registering the value assigned to that connection, a recorder, and means controlled by said registering means for operating said recorder responsive to the aggregate value of connections reaching a predetermined total.

15. 12. In a telephone or like system having a subscriber's line and means for including said line in different telephone connections at different times, each such connection having an arbitrary value assigned to it, a primary register controlled by each connection for registering the value assigned to that connection, a secondary register, means operated by said primary register for storing a marking in said secondary register responsive to the registered aggregate value of connections reaching a predetermined value, said secondary register thereafter controlled by said stored marking independently of said primary register to register said aggregate value of connections.

30. 13. In a telephone or like system having a subscriber's line and means for including said line in different telephone connections at different times, each such connection having an arbitrary value assigned to it, a primary register controlled by each connection for registering the value assigned to that connection, a secondary register, means operated by said primary register for storing a marking in said secondary register responsive to the registered aggregate value of connections reaching a predetermined value, said secondary register thereafter controlled by said stored marking independently of said primary register to register said aggregate value of connections, and means operated automatically by said secondary register after it has registered said aggregate value of connections for causing said storing means to efface said marking.

35. 14. In a telephone or like system having a subscriber's line and means for including said line in different telephone connections at different times, each such connection having an arbitrary value assigned to it, a primary register controlled by each connection for registering the value assigned to that connection, a normally non-conductive neon tube, means operated by said register to strike said tube responsive to the registered aggregate value of connections reaching a predetermined value, a secondary register controlled by said tube, said secondary register operated in accordance with the operation of said primary register responsive to said striking of said tube.

40. 15. In a telephone or like system having a subscriber's line and means for including said line in different telephone connections at different times, each such connection having an arbitrary value assigned to it, a primary register controlled by each connection for registering the value assigned to that connection, a normally non-conductive neon tube, means operated by said register to strike said tube responsive to the registered aggregate value of connections reaching a predetermined value, a secondary register controlled by said secondary register operated in accordance with the operation of said primary register responsive to said striking of said tube, and means automatically controlled by said secondary register

15

after its operation for again rendering said neon tube non-conductive.

16. In a telephone or like system having a subscriber's line and means for including said line in different telephone connections at different times, each such connection having an arbitrary value assigned to it, and means controlled by the last of a plurality of telephone connections including said line for registering the aggregate value of said connections.

17. In a telephone or like system, subscribers' lines, means individual to each of said lines operated in accordance with the fee chargeable to the subscriber for his use of that line, apparatus common to said lines, and means controlled by said first means for automatically associating said apparatus individually with any of said lines responsive to the accumulation of a predetermined total fee chargeable for the use of that line.

18. A system as claimed in claim 17, wherein said predetermined total fee, responsive to the accumulation of which said common apparatus is associated with a subscriber's line, differs for different subscribers' lines.

19. In a telephone or like system, a subscriber's line having individual line equipment, an adding

5

register associated with said line equipment and operated on successive calls from said line to accumulate a registration indicative of the total charge for said calls, and means controlled by said register for producing a circuit change in said line equipment responsive to the accumulation of a registration indicative of a predetermined total charge.

20. In a telephone or like system having a subscriber's line and equipment for extending calls therefrom, each call including a telephonic path, another path independent of said telephonic path, means for registering said calls on a unit call basis, and means controlled by said last means over said other path for recording said calls on a block call basis.

21. In a telephone system having subscribers' lines and equipment for making calls from said lines, means common to said lines controlled by the making of a call from any particular one of said lines for registering another call made previously from said particular line.
